(57) **CLAIM**

The ornamental design for a bracket and rod assembly as shown and described.

DESCRIPTION

FIG. 1 is a front perspective view of the bracket and rod assembly of the present invention;

FIG. 2 is a front elevational view of the bracket and rod assembly shown in FIG. 1;

FIG. 3 is a rear elevational view of the bracket and rod assembly shown in FIG. 1;

FIG. 4 is a left side elevational view of the bracket and rod assembly shown in FIG. 1;

FIG. 5 is a right side elevational view of the bracket and rod assembly shown in FIG. 1;

FIG. 6 is a top view of the bracket and rod assembly shown in FIG. 1;

FIG. 7 is a bottom view of the bracket and rod assembly shown in FIG. 1;

FIG. 8 is a front perspective view of the bracket of the bracket and rod assembly shown in FIG. 1;

FIG. 9 is a front elevational view of the bracket shown in FIG. 8;

FIG. 10 is a rear elevational view of the bracket shown in FIG. 8;

FIG. 11 is a left side elevational view of the bracket shown in FIG. 8;

FIG. 12 is a right side elevational view of the bracket shown in FIG. 8;

FIG. 13 is a top view of the bracket shown in FIG. 8; and, FIG. 14 is a bottom view of the bracket shown in FIG. 8. The drawings illustrate a bracket and rod assembly and the bracket of the assembly, as shown in the drawings. Contour lines are included in the various views of FIGS. 1 through 14 to depict surface curvature, flatness and/or other shapes.

(Continued)

Illustrative portions that are depicted in broken lines, are shown to put the present invention into context, and form no part of the claimed design.
